[57] CLAIM

The ornamental design for a ball-point pen, as shown and described.

DESCRIPTION

FIG. 1 is a perspective view of the front, top and right side of a ball-point pen showing my new design;
FIG. 2 is a front elevational view thereof;
FIG. 3 is a rear elevational view thereof;
FIG. 4 is a left side elevational view thereof;
FIG. 5 is a top plan view thereof;
FIG. 6 is a bottom plan view thereof;
FIG. 7 is a side elevational view with the top removed thereof, the appearance being the same about the entire circumference;
FIG. 8 is a top plan view thereof;
FIG. 9 is a bottom plan view thereof;
FIG. 10 is a front elevational view of the top when removed from the pen;
FIG. 11 is a rear elevational view thereof;
FIG. 12 is a left side elevational view thereof;
FIG. 13 is a top plan view thereof; and,
FIG. 14 is a bottom plan view thereof.
